United States Patent Office

Des. 232,888
Patented Sept. 24, 1974

232,888

DISPLAY STAND

Delmer D. McCommon, Newport Beach, Calif., assignor to Packers Bar M Meat Co., Los Angeles, Calif.

Filed Nov. 13, 1972, Ser. No. 305,703

Term of patent 14 years

Int. Cl. D6—04

U.S. Cl. D6—153

Fig. 1.

Fig. 2.

FIG. 3.

FIG. 4.

FIG. 1 is a front elevational view of the display stand showing my new design;

FIG. 2 is a top plan view thereof;

FIG. 3 is a right side elevational view thereof as viewed in FIG. 1; and

FIG. 4 is a rear elevational view thereof.

The side of the display stand which is not shown has substantially the same appearance as the side which is shown.

I claim:

The ornamental design for a display stand, substantially as shown and described.
